UNITED STATES PATENT OFFICE

2,221,810

ICE TRAY

James H. Miner, Meridian, Miss.

Application July 29, 1937, Serial No. 156,388

13 Claims. (CL 62—108.5)

The invention pertains to ice trays for refrigerators and consists in the features and in the combination and arrangement of parts hereinafter described and particularly pointed out in the claims.

In the accompanying drawing

Figure 1 is a plan view of the invention.

Fig. 2 is a plan view showing the relation of the parts when the two-part grid is operated by a movement of the hand lever in one direction.

Fig. 3 illustrates the action when the hand lever is moved to a greater extent than shown in Fig. 2.

The tray proper illustrated at 1 may be of substantially ordinary form having elongated sides and end walls which may incline upwardly and outwardly from the bottom of the tray. Within this tray a divider or grid is located, consisting of two main portions. Each main portion comprises a longitudinally extending bar 2 set up on edge, and fins or partition plates 3 extending laterally from these bars 2 and dividing the space within the tray into cube forming chambers or pockets.

The bars 2 of the grid sections normally lie close together, and each is provided with a projection at 4 so related in respect to each other that the end of a lever 5 can be thrust between these projections when the parts are in normal position, so that by then operating the lever, one of the grid sections will move towards the right, while the other grid section moves towards the left, and in this movement of the hand lever, the grid bars 2, 2 will be separated from each other laterally, as will be seen by comparing Fig. 1 with the position of the grid bars in Fig. 2.

In order to secure this lateral separation of the laterally extending grid bars 2, 2, the projections 4, 4 may have their opposing faces inclined as indicated at 6, so that the first part of the movement of the lever 5 will cause a lateral separation of the longitudinally extending bars 2, and this is immediately followed by a relative movement of these bars in the direction of their length, but in opposite directions. The ends of the center bars 2 of the grid sections engage blocks 7 attached as by vulcanization to the end walls of the tray. These blocks are of rubber or other yielding material capable of recovering its form after being distorted as a result of pressure thereon.

These blocks of rubber or like material occupy space within the tray which otherwise would be occupied by the ice. In effect they provide areas free from ice, which will allow the

portions of the grid, such as the longitudinally extending bars 2, 2, to have movement when subjected to pressure in the proper direction.

In the present case the rubber block permits the grid sections to move lengthwise of the tray relative to each other, the said rubber block distorting under the pressure exerted by the grid bars, but recovering their previous form when this pressure is released. These rubber blocks do not extend entirely across the end walls of the tray, but leave spaces at 8 which may be occupied by the ice.

The partition walls or fins 3 of the grid sections are desirably formed of metal having some yielding or spring quality. They are integrally connected with the longitudinal bars or partitions 2, and may flex slightly under pressure when the partition or bar 2 to which they are attached, is moved lengthwise. The ends of the fins 3 may be inclined to accord with the upward and outward inclination of the side walls of the tray.

Fig. 3 illustrates the position of the parts when the hand lever 5 is moved towards the left. The insertion of the tool 5, which it will be noticed is wedge-shaped, serves to give an initial separating tendency to the longitudinally extending bars 2. The tray may be made of thin metal so as to flex slightly under the pressures to which it is subjected. For instance, as the bars 2 of the grid are spread apart laterally the sides of the tray may flex slightly to accommodate this lateral spreading of the grid sections, together with the cubes located in the chambers or pockets thereof.

It will be observed in Fig. 3 that the full stroke of the lever has taken place and that the bars 2 of the grid have not only moved to their full limit in opposite directions, but have approached each other from their spread apart condition of Fig. 2, relieving the ice cubes of further pressure.

One side of the grid can be removed without the other so that one half the cubes can be withdrawn from the tray by removing one half 45 the grid.

The operating lever may be of different forms from that shown so that the action might take place while the tray is in the absorber chamber.

The action of the lever will be to break or crack any frozen joint between the faces of the lengthwise extending bars of the grid and also to crack the ice cubes from the tray.

The center bars 2, 2 of the grid may have 55

broad end surfaces where they bear on the rubber to prevent undue wear.

The invention is not limited to the form of the invention shown except as stated in the appended claims.

I do not limit myself to the use of rubber blocks as the means for occupying space that might otherwise be occupied by the ice, which would unduly resist the endwise movement of the center bars of the grid.

The cracking of the ice from the tray requires but a small degree of movement of the grid. The fins being flexible, will crack the ice cubes apart therefrom as said fins flex.

15 In place of the solid rubber members these may be formed hollow. One purpose of these members is to provide for the easy movement of the grid member or members, in respect to a space not occupied by ice. The hollow rubber member would accomplish the result while offering practically no resistance to the movement of the grid or to members making up the complete grid. The hollow rubber or yielding member of other material will be water proof in the 25 sense that water will be excluded from its interior, so that the desired end of providing a space free from ice will be accomplished. The rubber block may be inflated or may simply be in the form of a hollow rubber member, readily 30 yielding to pressure.

I do not claim broadly herein yielding means which permits movement of one part of the organization relative to another part for breaking the ice cubes away from their seats, such 35 subject matter being included in my application Serial No. 141,771, filed May 10, 1937.

I claim:

1. An ice tray for refrigerators comprising a tray proper and a grid therein, said grid being 40 in sections, each of which comprises a bar or partition extending lengthwise of the tray adjacent the other at the lengthwise center thereof, and substantially from end to end of the tray, fins attached to each of said bars and extending 45 transversely of the tray to form ice cube compartments, and means removably engaging said bars for operating said bars in opposite directions longitudinally of the tray, said lengthwise extending bars being provided with lugs between 50 which a wedge shaped tool is inserted to move said bars in opposite directions, said tool acting to spread said bars, substantially as described.

2. An ice tray organization for refrigerators comprising a tray, a grid therein in two sections, each having a partition extending longitudinally lengthwise of the tray substantially 55 centrally thereof, and juxtaposed relative to the partition of the other section, fins extending from said partitions in a direction transversely of the tray to the sides thereof, and means for operating the partitions of the grid relative to the tray and to each other, said means moving the said partitions away from each other in a direction transversely of the tray and in a direction 60 lengthwise of the tray, substantially as described.

3. An ice tray organization according to claim 2 in which the fins are yieldable in respect to the longitudinal partition which carries them.

4. An ice tray organization including a tray 70 proper made up of side and end walls bearing substantially a fixed relation to each other, said tray being of conventional longer than wide shape, a grid composed of two sections, each comprising a partition member extending substantially from end wall to end wall, but each 75

adapted to have comparative movement from one end wall of the tray towards the other end wall thereof while maintaining its position in the same horizontal plane, said partitions being juxtaposed at the center of the tray, and yielding members between an end of each grid section and the adjacent end wall of the tray upon which said grid end bears, and means for moving the grid sections lengthwise of the tray against the yielding members, said yielding members occupying space that otherwise would be occupied by ice, which would prevent movement of the tray lengthwise thereof, said longitudinally extending partitions having fins extending laterally therefrom with their ends free to move 15 along the side walls of the tray, substantially as described.

5. An ice tray organization for refrigerators comprising a tray proper, a grid therein in sections each comprising a bar or partition extending longitudinally of the tray at the center thereof, and initially substantially in contact with the other bar, said bars having fins extending laterally thereof to the side walls of the tray and operating means for spreading the bars, said 20 means also operating the bars longitudinally and in opposite directions relative to each other, substantially as described.

6. An ice tray organization according to claim 2 in which the operating means after moving 30 the bars longitudinally relative to each other in separated relation operate the bars laterally towards each other, substantially as described.

7. An ice tray organization comprising an ice tray proper, having side, end and bottom walls 35 integrally connected together, a removable grid therein made in two separately formed sections, each having a bar or partition member extending lengthwise of the tray, arranged face to face, and each having laterally extending fins, and 40 means for operating said bars lengthwise of the tray relative to each other and to the end walls of the said tray.

8. An ice tray organization according to claim 7 in which the relative movement between the 45 bars takes place in opposite directions simultaneously.

9. An ice tray organization comprising a tray, a removable grid of two separately formed sections, each having a longitudinally extending 50 bar with fins spaced apart along and extending laterally therefrom, and movable therewith, said bars being arranged face to face, and means for operating the bars simultaneously in the direction of their length oppositely, substantially as 55 described.

10. An ice tray organization comprising a tray, a grid in two sections extending side by side lengthwise of the tray, and rubber blocks at each end of the tray and means for operating 60 the grid sections in opposite directions relative to each other, each section of the grid being controlled in its movement by one of the rubber blocks individual thereto.

11. An ice tray organization for refrigerators 65 comprising a tray proper, a grid removably mounted therein composed of separately formed main bars extending lengthwise of the tray, each having a set of fins projecting laterally therefrom, said main bars and fins dividing the space 70 within the tray into cube forming pockets, and a body of yielding material within and between parts of the organization, said body of yielding material occupying space which otherwise would be occupied by the ice, said body allowing, under 75

pressure, relative movement between parts of the organization for breaking the cubes of ice away from their seats, and means for operating said bars lengthwise of the tray simultaneously in opposite directions, substantially as described.

12. An ice tray organization comprising a tray, a grid in two separately formed sections extending side by side lengthwise of the tray, and each capable of moving in the direction of its length 10 towards an end of the tray, means for moving said sections simultaneously in opposite directions lengthwise of the tray, and yielding means occupying part of the space within the organi-

zation, in contact with a part of the grid and distortable by the movement of the grid sections, substantially as described.

13. An ice tray organization according to claim 7 in which there is at each end of the tray, and 5 bearing upon the end wall thereof, a block of yieldable material, one of which is borne upon by one of the longitudinally extending bars of the grid, and the other of which is borne upon by the other longitudinally extending bar of the 10 grid, substantially as described.

JAMES H. MINER.
